CLAIM

The ornamental design for stylus pen charger, as shown and described.

DESCRIPTION

1. Stylus pen charger

1.1 : Perspective

1.2 : Front

1.3 : Back

1.4 : Left

1.5 : Right

1.6 : Top

1.7 : Bottom

1.8 : Perspective

1. Purpose of this design product: The present design product is used for charging and storing of the stylus pen.

(Continued)

2. The evenly broken lines in the drawings depict the portions of the stylus pen charger which form no part of the claimed design.

1 Claim, 8 Drawing Sheets
